SCAFFOLD CLAMP

Marius Artique, Geneva, Switzerland

Application July 23, 1943, Serial No. 495,882
In Switzerland August 8, 1942

6 Claims. (Cl. 304—40)

This invention relates to dismountable or semi-dismountable constructions such as scaffoldings, towers, sheds, huts, foot bridges, galleries, platforms, stagings, travelling cranes, iron trestles or tube frames, centerings for concrete arches or vaults or similar buildings and has more particular reference to constructions of this category made up of sets of solid or tubular bars or like elements of cylindrical or prismatical cross section assembled or lashed together in a temporary fashion so as to lend themselves to easy dismantling whenever required.

An object of this invention is to provide a new or improved device for readily assembling, securely and yet removably, the bars or elements of which temporary constructions of the aforesaid category are made up.

Another object of the invention is to provide an assembling device as aforesaid comprising, in combination with a central carrier part forming a double cradle, clamps for the bars and tightening bolts for said clamps, the arrangement being such that during manipulation of the device neither damage of the clamps nor loss of the bolts can be encountered.

A further object of the invention is to provide an assembling device as aforesaid whose parts are so shaped and co-related as to permit mounting and dismantling thereof to be performed without requiring mechanical operations, the clamps being moreover guided towards and off tightening position without any risk of becoming warped or distorted.

A still further object of the invention is to provide an assembling device as aforesaid capable of being manufactured cheaply from sheet iron blanks foldable to proper carrier and clamp formations adapted to cooperate so as to accommodate therebetween the bars or like elements of the construction which require to be clamped together.

With these and such other objects in view as will incidentally appear hereafter, the invention comprises the novel construction and combination of parts that will be now described in detail with reference to the accompanying diagrammatic drawings exemplifying the same in a suitable embodiment and forming a part of the present disclosure.

In the drawings:

Figure 1 is an elevational view of the device illustrating how it can be used for assembling together two tubular bars arranged at right angles, the left hand side of this figure showing one of the upper clamps in closed down position while

its right hand side shows the companion upper clamp in opened up position as if to permit insertion of the upper bar.

Figure 2 is a top plan view of the device, the left hand side of this figure corresponding to the left hand side of Fig. 1 while in its right hand side said companion upper clamp is assumed to be omitted, the location of the upper bar being shown in chain lines.

Figure 3 is a plan view showing how the central carrier part of the device can be made by curling pairwise the opposite ends of the four legs of a cross-shaped blank cut from sheet iron, said curling being effected in opposite directions to provide a double cradle structure.

Figure 4 is partly an elevational view (left) and partly a transverse sectional view (right) of the central carrier or double cradle part shown in Fig. 3.

Figure 5 is a plan view showing how each upper clamp can be made from a sheet iron blank, the parts drawn in chain lines on each side being the parts which are folded down to form depending lugs defining the hinge sockets sidewise.

Figure 6 is partly (left) an elevational view and partly (right) a sectional view on the line VI of Fig. 5 of one of the upper clamps.

Figure 7 is an inverted plan view of the upper clamp shown in Fig. 6.

Figure 8 is an end view of the upper clamp shown in Fig. 5.

Figure 9 is an elevational view of the hinge or trunnion and associated bolt, said hinge being accommodated in each socket of the carrier part.

Figure 10 is a top plan view of Fig. 9.

Figure 11 is an end view of Fig. 9.

Like reference characters designate like parts throughout the several views.

In the embodiment shown, the device comprises a central carrier part A providing upper and lower recesses or cradles for the respective tubular bars 2, 1 which require to be temporarily and yet securely assembled, for example to constitute a scaffolding, said bars being arranged in superimposed relation and at right angles to each other as shown in Figs. 1 and 2. The upper cradle cooperates with a pair of companion clamps 3, 3 substantially of arch shape capable of being temporarily held down by bolts 4, 4 engaged

50 through their slotted ends, said bolts being screwed down through sleeve-shaped hinges or trunnions 5, 5 pivotally housed in hinge sockets 6, 6 in side bulges formed by curled portions of the carrier part A. Each clamp 3 can be rocked up as shown on the right hand side of Fig. 1 to

permit insertion of the bar 2, whereafter the clamp 3 can be rocked down to resume its holding position as shown on the left hand side of Fig. 1. Likewise the lower cradle cooperates with clamps 3' fitted with bolts 4.

It will be understood that when in rocked off position, each clamp remains attached to the carrier part A of the device and is merely permitted to swing about an axis extending parallel to the bar or like element which requires to be clamped thereby. The bolts 4 cannot become lost as they remain set through the ends of the clamps. No machining operation is required for erecting the device or dismounting the same into its constituents.

The method of producing the improved assembling device as above-described will be easily understood from an inspection of Figs. 3 to 11 inclusive.

The central carrier part A and the clamps 3, 3' are each made from single blanks, preferably of sheet iron or steel.

As illustrated in Figs. 3 and 4, the blank from which the carrier part A is produced is cross shaped and its four legs a, b, c, d which are flared at their free ends and which originally occupy projecting positions as shown in chain lines in Fig. 3 are afterwards curled inwardly to assume the operative positions a', b', c', d'. To that effect, the legs a, b are curled upwardly of the major plane of the blank to provide a pair of upper arcuate bulges defining between them an intermediate concave recess or cradle for a bar 2, while the legs c, d are curled downwardly of said plane to provide a pair of lower arcuate bulges defining between them an intermediate concave recess or cradle for a bar 1. Said pairs of bulges extend at right angles to each other and form internal sockets adapted to accommodate revoluble hinges as will be described hereafter. Elongated holes a'', b'', c'', d'' in the carrier blank legs a, b, c, d form slots in the bulges after said legs have been curled as above-stated to assume their operative positions. Said slots are adapted to receive bolts 4 or like retaining members also set through the clamps and engaged into the hinges.

The clamps 3, 3' are also shaped from sheet metal blanks. The blank from which the clamp 3 is made originally has the outline shown by the chain lines, whereafter the middle portion of the blank is bowed to arch shape and the end portions e, f having slots e' and f', f'' are crimped down in hairpin fashion to form flaps projecting inwardly of the clamp arch span, while the side portions g, h, i, k are folded down at right angle to their original coplanar positions to form projecting lugs defining the hinge sockets sidewise and acting as side guides for proper positioning of the clamp.

Each bolt 4 has a reduced end 4' (Fig. 11) set into a sleeve hinge 5 having a notch 5' (Fig. 10) and accommodated in one of the sockets 6. This arrangement prevents the bolts from being clogged up by rust to their hinge sleeves.

In operation, the clamps 3, 3' are first rocked off the carrier or double cradle part A and the latter is then inserted between the bars 1, 2 extending at right angles to each other, whereafter the clamps 3, 3' are rocked back to bar-inclosing positions, and the bolts 4 are tightened until the bars are securely held. A reverse manipulation is effected to release the bars from the device.

Numerous minor constructional details might be changed without departing from the scope of

the subjoined claims wherein the word "retainer" involves any bolt equivalent.

What is claimed is:

1. A device for assembling scaffold bars or like building elements, comprising a carrier having a pair of opposite bar-receiving cradles disposed in superimposed and angular relation and defined between pairs of folded terminal portions of said carrier forming sockets, hinges in said sockets, rockable clamps cooperating with the cradles in lid fashion, and removable retainers set through the sockets and clamps and engageable with the hinges.
- 15 2. A device for assembling scaffold bars or like building elements, comprising a carrier having a pair of opposite bar-receiving cradles superimposed at right angles to each other, said cradles being defined between pairs of folded terminal portions of said carrier forming sockets, hinges in said sockets, rockable clamps of arch shape cooperating with the cradles in lid fashion, and bolts set through holes in the ends of the clamps and in the sockets and engageable with the hinges.
- 20 3. A device for assembling scaffold bars or like building elements, comprising a carrier having a pair of opposite bar-receiving cradles superimposed at right angles to each other, said cradles being defined between pairs of folded terminal portions of the carrier and providing sockets, hinge members in said sockets, rockable slotted clamps cooperating with the cradles in lid fashion, and bolts set through the slots in the clamps and sockets and engageable with the hinge members.
- 25 35 4. A device for assembling scaffold bars or like building elements, comprising a carrier having a pair of opposite bar-receiving cradles superimposed in right angular relation, said cradles being defined between pairs of arcuate slotted bulges forming sockets, notched hinge sleeves revolvably enclosed and confined within said sockets, rockable slotted clamps cooperating with the cradles in lid fashion, and bolts set through the clamp and bulge slots and having reduced ends engageable with the notches in the hinge sleeves.
- 40 45 5. A device for assembling scaffold bars or like building elements, comprising a carrier plate having a pair of opposite bar-receiving cradles superimposed in right angular relation, said cradles being defined between pairs of arcuate slotted bulges formed by terminally flared extensions of the carrier plate, said extensions being curled to provide socketed bulges, notched hinges snugly revolvable in the bulge sockets, rockable slotted clamps cooperating with the cradles in lid fashion, and bolts insertable through the clamp and bulge slots and having reduced ends engageable with the hinge notches.
- 50 55 60 65 70 6. A device for assembling scaffold bars or like building elements, comprising a carrier plate having a pair of opposite bar-receiving cradles superimposed in right angular relation, said cradles being delineated between pairs of arcuate slotted bulges defining inner sockets, notched hinge sleeves revolvable in said respective sockets, rockable slotted clamps cooperating with the cradles in lid fashion, each clamp comprising an arch portion terminating in inwardly crimped flaps and two pairs of angularly protruding side lugs, and bolts insertable through the coincident clamp and bulge slots and having reduced ends engageable with the hinge notches.
